US00D712423S

(12) **United States Design Patent**
Yang et al.

(10) **Patent No.:** US D712,423 S
(45) **Date of Patent:** ** Sep. 2, 2014

(54) **CELLULAR PHONE WITH GRAPHICAL
USER INTERFACE**

(75) Inventors: **Sooyoung Yang**, Seoul (KR); **Jaeyoung Lee**, Seoul (KR); **Eungyeong Gwon**, Seoul (KR)

(73) Assignee: **LG Electronics Inc.**, Seoul (KR)

(**) Term: **14 Years**

(21) Appl. No.: **29/426,024**

(22) Filed: **Jun. 29, 2012**

(30) **Foreign Application Priority Data**

Jan. 6, 2012 (KR) 30-2012-0000885

(51) **LOC (10) Cl.** 14-04

(52) **U.S. Cl.** ..... USPC **D14/486**

(58) **Field of Classification Search**

CPC G06F 3/048

USPC D14/485-495; 715/700-867, 961-978

See application file for complete search history.
